Filed July 7, 1967, Ser. No. 651,860
1 Claim. (Cl. 33—23)

ABSTRACT OF THE DISCLOSURE

An adapter for a conventional scribe including a portion adapted to be removably supported from a scribe in lieu of a pencil or pen element of the scribe and to support a felt tip marker therefrom whereby the scribe may be utilized to guide the movement of the felt tip marker.

The instant invention includes the provision of an adapter for a conventional scribe in the form of an assemblage adapted to removably support a felt tip marker therefrom and which includes means whereby the assemblage may be supported from a conventional scribe in lieu of the pen or pencil element normally supported by the scribe. By such an assemblage a felt tip marker may be utilized in conjunction with a scribe to form the letters of signs and other printed material in a professional-like manner.

The main object of this invention is to provide a means by which a conventional felt tip marker may be supported from a conventional scribe in lieu of the pen or pencil unit normally supported from the scribe.

Another object of this invention is to provide an assemblage in accordance with the preceding object which may be constructed in a manner so as to support various felt tip markers therefrom.

Still another object of this invention is to provide an assemblage constructed in a manner such that a conventional scribe may be readily adapted to support a felt tip marker therefrom.

A final object of this invention to be specifically enumerated herein is to provide an assemblage in accordance with the immediately preceding objects which will conform to conventional forms of manufacture, be of simple construction and easy to use so as to provide a device that will be economically feasible, long lasting and relatively trouble-free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a top plan view of a conventional form of scribe with the assemblage of the instant invention operatively supported therefrom and being utilized to support a conventional felt tip marker from the scribe;

FIGURE 2 is a fragmentary elevational view of the structure illustrated in FIGURE 1 and as seen from the section line 2—2 of FIGURE 1;

FIGURE 3 is an enlarged horizontal sectional view taken substantially upon a plane passing through the vertical center of the clamp portion of the assemblage by which the felt tip marker is supported;

FIGURE 4 is a perspective view of the assemblage comprising the instant invention by which a felt tip marker may be supported from a conventional scribe;

FIGURE 5 is a fragmentary perspective view of a modified form of scribe illustrating a modified form of assemblage constructed in accordance with the present in-

2

vention being utilized to support a felt tip marker from the modified form of scribe;

FIGURE 6 is a perspective view of the assemblage illustrated in FIGURE 5 by which the felt tip is supported from the modified form of scribe;

FIGURE 7 is a perspective view of still another modified form of assemblage by which a felt tip marker may be supported from the scribe illustrated in FIGURES 1 and 2; and

FIGURE 8 is a perspective view of a fourth modified form of assemblage for supporting a felt tip marker from a conventional form of scribe.

Referring now more specifically to the drawings the numeral 10 generally designates a conventional form of scribe including a main body portion 12 from which a guide pin assembly 14 is supported. The main body portion 12 also supports a tracing pen 16 and a pivoted support arm structure 18 which may be secured in adjusted rotated positions relative to the body portion 12. The support arm structure 18 includes a bifurcated free end portion including a pair of furcations 20 and 22 interconnected by means of a clamping screw 24. The free ends of the furcations 20 and 22 include opposing semi-cylindrical recesses (not shown) in which a cylindrical member may be secured in adjusted rotated position relative to the support arm structure 18.

A generally cylindrical pencil or pen assembly is conventionally clamped between the free ends of the furcations 20 and 22. However, in order to adapt the scribe 30 to support a felt tip marker such as that generally designated by the reference numeral 26 illustrated in FIGURES 1-3, an assemblage generally referred to by the reference numeral 28 is provided. The assemblage 28 comprises a split clamp assembly including a pair of generally semi-cylindrical resilient arm portions interconnected at one pair of adjacent ends. The free end of one of the semi-cylindrical arms or arm assemblies is notched and rolled outwardly and back upon itself tightly about a pivot pin 30 to which one end portion of an elongated spring latching member 32 is pivotally secured in the notched area of the rolled portion of the one arm assembly and the free end of the other arm or arm assembly is also notched and rolled outwardly and back upon itself to tightly clamp a latch pin 34 which generally parallels the axis of rotation of the latching member 32 and with which the hook end portion 36 of the latching member 32 may be releasably engaged to circumferentially contract the assembly 28 about the felt tip marker 26. The assemblage 28 includes an integral sleeve portion 38 remote from the free ends of the arms or arm assemblies which support the pins 30 and 34 and one end of a generally cylindrical support rod 40 is stationarily secured in the sleeve portion 38.

The extended end of the support rod 40 is of a diameter adapted to be clamped between the aforementioned semi-cylindrical recesses formed in the free ends of the furcations 20 and 22 and therefore the screw 24 may be utilized to cause the support rod 40 to be clamped between the furcations 20 and 22 and to thus support the felt tip marker 26 from the scribe 10 by means of the assemblage 28.

With attention now invited more specifically to FIGURES 5 and 6 of the drawings there may be seen a modified form of scribe generally referred to by reference numeral 10' and which includes furcations 20' and 22' similar to the furcations 20 and 22. The furcations 20' and 22' also include recesses (not shown) similar to the aforementioned recesses formed in the free ends of the furcations 20 and 22 and a split sleeve type assemblage generally referred to by the reference numeral 50 is removably clamped between the furcations 20' and 22'.

The split-sleeve type assemblage 50 includes a generally cylindrical body portion 52 including a diametrically en-

larged shoulder 54 on one end. The body portion 52 and the shoulder 54 are longitudinally split as at 56 and therefore the body portion 52 may be circumferentially contracted when clamped between the furcations 20' and 22'. A felt tip marker generally referred to by the reference numeral 58 and which is somewhat smaller in diameter than the felt tip marker 26 is disposed within the body portion 52 whereupon the clamping action of the furcations 20' and 22' will cause the felt tip marker 58 to be clamped in the body portion 52. Of course, the shoulder 54 carried by the upper end of the body portion 52 is adapted to abut and rest against the adjacent upper surface portions of the furcations 20' and 22'.

With attention now invited to FIGURE 7 of the drawings there may be seen an assemblage referred to in general by the reference numeral 60 and which is similar to the assemblage 28 except that in lieu of a pair of spring arms the assemblage 60 includes a continuous sleeve member 62 from which a support rod 64 similar to the support rod 40 is supported. The sleeve member 62, instead of defining a clamp assembly includes inwardly projecting circumferential ribs 66 spaced longitudinally therealong which are adapted to frictionally engage and thus removably retain the felt marker 26 within the sleeve member 62.

With attention now invited more specifically to FIGURE 8 of the drawings there may be seen an assemblage generally referred to by the reference numeral 68 and which is quite similar to the assemblage 60 except that in lieu of the axially spaced and circumferentially extending ribs 66 for frictionally retaining the felt tip marker 26 therein, the sleeve member portion 70 of the assemblage 68 includes thread means 72 defining threads of relatively great pitch which may be utilized to removably threadedly secure a modified form of felt tip marker provided with similar external threads. Of course, the relatively great pitch of the thread means 72 enables a corresponding felt tip marker such as the marker 26 but provided with similar external threads to be quickly removably secured in the sleeve member 70 of the assemblage 68.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In combination with a scribe of the type including a clamp assembly adapted to removably clampingly engage a pencil or pen element of a relatively small diameter, 5 an adapter holder comprising a sleeve member adapted to encircle a second relatively large diameter size felt tip marker, said sleeve member being split, resilient and including spaced apart free ends, said sleeve member including a shank portion carried by a portion thereof generally diametrically opposite said free ends, said shank portion generally paralleling the longitudinal center line of said sleeve member and including one end portion projecting endwise outwardly of the corresponding end of said sleeve member, said one end portion of said shank portion being of a diameter generally equal to said small diameter, 10 said one end portion being removably clamped in said clamp assembly, a hooked latching member including a shank end and a hooked end, the shank end of said latching member being articulatively anchored to one of the free ends of said sleeve member centrally intermediate the axial ends of said sleeve member, the other of said free ends of said sleeve member being notched centrally intermediate the axial ends of said sleeve member and rolled outwardly and back upon itself, a latch pin secured 15 in and at least substantially encircled by the rolled portion of said other free end of said sleeve member, the free hooked end of said latching member being removably engaged with the portion of said latch pin extending through the notched area of said rolled portion of said 20 other free end with said sleeve member circumferentially contracted so as to be adapted to tightly clamping engage said marker.
